MICA SPLITTING PROCESS AND APPARATUS

Harry H. Burton, Worcester, Mass., assignor, by
mesne assignments, to Aerovox Corporation, a
corporation of Massachusetts

Application February 19, 1943, Serial No. 476,435

24 Claims. (Cl. 125—24)

1

This invention relates in general to mica splitting; more particularly, it contemplates the rapid and economical division or separation of books or thin blocks of sheet mica, each into a number of thin films, such as condenser splits or sheets, or, as desired, into still-thinner "splittings" or mica flakes, such as are required for the manufacture of built-up board or plate mica. The present application is a continuation-in-part of my copending application Serial No. 454,722, filed August 13, 1942.

There have been numerous attempts to obtain mechanical splitting or filming of sheet mica; however, the industry still is wholly dependent upon knife-splitting (a manual operation requiring the utmost in patience and dexterity) for the commercial production of these extremely thin and delicate mica sheets or films. Occasionally, the wielder of a splitting knife encounters a book of mica which yields readily to the desired filming or splitting, but in most cases, this knife-splitting, even for operators of long training and experience, is a very slow and tedious operation; also, it has always been extremely wasteful of the material, since a great many films despite the most careful manipulation of the splitting knife, undergo scratching or fracture in the act of peeling them from the block or book, this being due not only to the very fragile character of the material, but also, in even greater measure, to the wide and unpredictable variations encountered in the strength and resistivity to splitting of the natural bond or adhesion in the different planes of cleavage of the material and in different parts or zones of any given plane of cleavage.

Numerous efforts have been made to overcome or to materially reduce this bond or adhesion between the layers or laminations of sheet mica; one such treatment, for example, was to first heat the mica to just under redness and then to quench it in water. Up to now, all such attempts at pre-conditioning of the mica, to facilitate its splitting or filming have met with failure, due primarily to the inability of the water, or other bath liquid employed, to penetrate appreciably between the layers or laminations, or to materially affect the strong bond between their opposed surfaces.

My invention, in one of its aspects, contemplates a pre-conditioning of the book mica to facilitate its splitting or filming, that does in fact materially break down and minimize this bond or adhesion, without harm to the delicate films themselves, this treatment being based on my discovery that a remarkably widespread liquid penetration between even the most strongly bonded films can be obtained, by soaking the books in a water bath containing a "wetting agent" or surface-active material of special constituency and properties. In another of its aspects my in-

2

vention contemplates a splitting or filming technique or practice, made feasible in large degree by the aforesaid preconditioning of the material, which not only eliminates the great amount of waste and loss that inevitably occurs with knife-splitting, but enables the splitting or filming operations to be rapidly performed by unskilled operators needing no more than a few hours of training and instruction—in contradistinction to the many months of practice and instruction required to train an operator for knife-splitting.

Other and further objects and advantages of my invention will be made apparent by the following detailed description thereof, taken in connection with the accompanying drawings, in which—

Fig. 1 is a sectional view, exemplifying a step by which the book mica is conditioned, according to my invention, for splitting or filming.

Fig. 2 is a perspective view, illustrating an implement employed by an operator in the splitting or filming of book mica according to my invention.

Figs. 3, 4, 5, 6 and 7 are a series of line diagrams representing an operator's successive manipulations of a mica book, relative to the implement of Fig. 2, in securing splitting or filming according to my invention.

Fig. 8 is a sectional view of an implement similar to that of Fig. 2, but equipped with adjustable means by which to predetermine the thickness of the successive films that are split off from the book.

Like reference characters refer to like parts in the different figures.

The conditioning of the mica, according to my invention, is diagrammatically shown by Fig. 1, the latter simply illustrating a suitable receptacle 1, filled to the level 2 with liquid, in which are submerged the books 3, 3 of sheet mica. Preferably, but not necessarily, such books have previously been cut, trimmed and reduced in thickness to substantially the conditions under which they would be subjected to knife-splitting.

It has long been recognized in this art that the bond or adhesion between the laminations of sheet mica is practically impervious to water, as well as to a great variety of other liquids and solutions by which it has been sought, without success, to break down or reduce said bond, before attempting to divide and sub-divide the material into thin films, or still-thinner "splittings," as the case may be. I have discovered, however, that a very marked reduction in the strength of this bond is obtained by soaking the mica books or blocks, such as shown at 3, 3, in a water bath containing in small quantity an organic water-soluble "wetting agent" or surface-active material of the type exemplified by the aliphatic

esters of dicarboxylic and sulfodicarboxylic acids which are known to effect a marked reduction in the surface tension of water, for example, a "wetting agent" of substantially the properties possessed by the substance known commercially as "aerosol," a dioctyl ester of sodium sulfosuccinate. I have found that only a small amount of such a wetting agent is required to reduce to a very low value the interfacial tension between water, mica and air, thus to make the bath liquid capable of permeating, penetrating, and materially breaking down the strength of the bond or adhesion between the laminations of sheet mica in book or block form; that is to say, a highly satisfactory bath for this purpose can be made by the addition of twenty-five drops of a dilute solution of "aerosol" ("aerosol O. T. 10%") to each quart of water. The bath may be improved, if desired, by the addition of a few drops of ammonia, the effect of this being to clean any fog or film from the surfaces of the thin mica laminations or sheets into which the book is readily divisible, as hereinafter described.

Prolonged soaking of the mica in the conditioning bath of my invention has no harmful effect whatsoever on the material, nor do the thin films or splittings into which the mica books are subsequently divided suffer any impairment of their di-electric strength, or the other properties, that render thin sheet mica so indispensable in the manufacture of condensers, spark plugs, radio tubes, and other electric devices. But my improved bath liquid does act very noticeably on blocks or books of sheet mica submerged therein, to render them readily susceptible to division into thin films and splittings; this action, unobtainable by any soaking of mica books in ordinary water and other liquids of relatively high surface tension, is possibly explainable on the theory that my bath liquid, by virtue of its extremely low surface tension, is able very quickly to spread and penetrate through minute gaps, breaks, or weak zones of the bond in each plane of cleavage, the liquid thus seeping inwardly to attack the bond in its unweakened areas and to obtain its gradual disintegration. Whatever the action may be, it is a fact that blocks or books of mica, after soaking in a bath of the above-described character, are much less resistant to splitting or filming; with some mica, only a relatively short period of soaking is required to effect a material breaking down of the bond between the laminations, but with other mica where the bond is stronger to start with, the soaking period may need to be of several hours duration before the bond is sufficiently weakened to permit of easy splitting or filming. In any case, I have found that the action of my conditioning bath is best served by maintaining same at a fairly warm temperature, not, however, as high as the boiling point of the water or other liquid ingredient of said bath.

Book mica which has been soaked or treated as above described for a sufficient period to materially weaken the strong bond or adhesion between the laminations, can of course be divided and sub-divided by a knife-splitting operation that requires the exertion of much less force on the part of the operator to push the knife through and between the laminations of the material, thereby speeding up the operation and decreasing to some extent the spoilage and fracture of the films. But even as thus made easier, such knife-splitting practice is always fraught with the hazards of film fracture and scratching,

due to the fact that the laminations of the book rarely present a mathematically flat surface; these deviations from absolute flatness, though very slight and minute, make it very difficult to open up a plane of cleavage with the splitting knife without damaging or fracturing the film surfaces on one side or the other of said plane. Although my above-described soaking of book mica is of substantial benefit in conditioning the mica for knife-splitting, its greatest usefulness lies in the fact that it renders the mica susceptible to splitting or filming by the novel technique or practice now to be described, which not only avoids the numerous inherent disadvantages of knife-splitting, but enables the books to be rapidly divided and sub-divided without appreciable waste by operators having only a minimum of skill, experience and training.

Such new splitting or filming technique or practice is based on equipping each operator with one or more implements or devices of the character depicted by Fig. 2, such implement or device, designated as a whole by the numeral 4, being a hollow body of any suitable material such as metal, which is preferably secured to a table or bench 5 at which the operator works, and which presents as its working face a convex surface 6.

Said surface 6 preferably faces the operator, and rises from the table surface 5 at a convenient distance from the edge thereof, the implement or device 4 being held in this position by any suitable means, here shown as in the form of a tubular extension 7, projecting from the bottom surface 8 of said implement or device 4, and received snugly in a hole or opening 9 of the table or bench 5. This tube 7 communicates with the interior of the body 4, and at its other end is connected, as by a tube 10, with any suitable source of vacuum, such as a suction pump or air exhauster, not shown.

Such partial vacuum or suction thus maintained interiorly of the hollow body is made effective on its convex working surface 6 by suitable slots or openings 11, 11 in the wall 12 that provides said surface 6, these suction apertures or openings 11, 11, as best shown in Fig. 2, being preferably a series of narrow slits, in herringbone arrangement, near the bottom of the working surface 6; in any event, they occupy only a small portion of the total area of convex working face 6, their effectiveness, as a suctional gripping and holding means, being limited to a relatively narrow band or zone extending across the working surface 6, which latter, by reason of its substantial convexity, is to be noted as falling away or receding in the major portion of its area from said suction band or zone provided by the slits 11, 11.

In the utilization of such an implement or device for the progressive splitting or filming of books or blocks of sheet mica, according to my invention, the operator, either seated at or standing before the table 5, removes a conditioned mica book of appropriate size or area from the bath of Fig. 1 and presents it face foremost to the aforesaid suction zone or band of the surface 6, taking care only to see that the book's face portion so opposed to and seized by the suction apertures is a portion which is relatively close to an edge or extremity of the book. The effect of such a presentation is for the book 3 to be seized and supported by the suction, against the working surface 6, in substantially the tangential relationship indicated by the diagram, Fig. 3—that is, with its face seized and held suctionally against

the surface 6 only near the book's edge portion 13, the remainder of said face and the opposite edge or extremity 14 of said book being in spaced relation to the surface 6, because of the latter's convexity. With the book's support thus transferred to the suction device or implement 4, as indicated by Fig. 3, it only remains for the operator to exert a light thumb or finger pressure against the book in the vicinity of its free edge 14; such pressure, in the direction of the working surface 6 as indicated by the diagram Fig. 4, procures a cleavage starting at edge 13 between the suctionally-gripped surface lamination 15 and the book's remaining laminations, the latter collectively retaining their flat or planar character, and thereby peeling away gradually from the former (the suctionally-gripped surface lamination 15) as the pressure forces the book's edge 14 nearer and nearer to the surface 6, (see diagram Fig. 5). During this peeling action, the suctionally-held surface lamination 15 being thin and flexible enough to conform itself to the curvature of the surface 6, is supported and sustained by said surface. Thus, there is no appreciable strain or stress imposed on the lamination 15 by this peeling-away from it of the flat relatively rigid body 16 constituted by the book's other laminations.

That is to say, the above-described movement or manipulation is one which effects a gradual planar tilting or rolling of this rigid body, relative to the curved surface 6, in such a manner that the relation of virtual tangency between its plane and the surface 6 is always preserved, notwithstanding that the movement causes the zone of tangency to shift progressively farther and farther away from its original position, i. e., the suction zone defined by the slits 11, 11. Thus as the book edge 14 comes nearer to the surface 6, the opposite edge 13' of body 16 is all the time moving away from said surface, giving opportunity for the operator, at or about the stage depicted by Fig. 5, to seize the body 16 between thumb and finger, to hasten the peeling away from the lamination 15 by an upward swinging movement, (see diagram Fig. 6), about a pivot or axis afforded by the contact or proximate contact, of edge 14 with surface 6.

With the body 16 thus peeled away and stripped clear from the suctionally held lamination 15, the latter (see diagram Fig. 7) is left standing alone against the surface 6, in position for ready removal, either by pulling it off said surface, or by a momentary release of the vacuum to allow its drop by gravity into a convenient receptacle, not shown; such release or momentary breaking of the vacuum can be effected in any convenient way, as by providing a suitable valve, not shown, in the tube or connection 10, for letting atmospheric air into the interior of the device 4, upon being opened momentarily by the operator's depression of a suitably placed foot treadle, or the like.

As soon as any such separated lamination 15 is removed from the surface 6, the operator simply re-presents the same book, in its slightly reduced or thinner form 16, to the suction apertures 11, 11, and repeats the above-described manipulation to obtain the separation of another external layer or lamination, and so on until the book by successive separations therefrom of its layers or laminations is completely divided, or is reduced to a residue so extremely thin that the relative stiffness or rigidity needed for the above-described manipulation is no longer present.

However, the needed stiffness or rigidity is usually not lost or eliminated until the book residue has been reduced to a thickness of about 1 or 2 one-thousandths of an inch, thin enough, that is, for the residue itself to constitute a mica film or splitting that is fully as useful for many electrical purposes as any of the thinner films or laminations into which the major portion of the book, in the manner above described, may have been previously divided and sub-divided.

Such filming operation involving, in effect, successive peelings away of the book residue from the layer undergoing separation (in contradistinction to knife-splitting where the layer undergoing separation is peeled away from the book) is a cycle of simple manipulation that can be quickly imparted and taught to operators who have had no previous experience in the handling of mica; with only little practice, such operators are able to perform the manipulations so speedily as to obtain a much higher rate of production of mica films and splittings than can be obtained by an experienced knife-splitter; moreover, by my method of splitting, the waste or spoilage (which is always very heavy with knife-splitting) is reduced to an almost negligible factor. The material is successively presented to and manipulated on the implement or device 4, always in the same way, by a routine which is simple and easily learned; in fact, it is perfectly possible for sheet mica, under the conditions and with the equipment contemplated by my invention, to be split or filmed by blind operators, once they have been taught the hand movements that are involved.

It will be understood, of course, that the implements or devices 4 will ordinarily be provided in a variety of sizes, those of small size being used with small area books, and those of larger size being used with large area books.

Fig. 8 shows a suction device or implement, similar in construction and operation to that of Fig. 2, but equipped with an arrangement by which to adjust or predetermine the thickness of the films that are split off in succession from the book material. For this purpose, the working surface 6' of the suction device or implement 4 is formed just below the suction slits 11', 11' with a small hole 17, in which is slidably but snugly received a stem 18, the latter at its outer end having an upward projection 19, in the form of a small chisel-point substantially paralleling the surface 6 and of sufficient sharpness to penetrate by a minute amount the edge of a book or block of sheet mica, when the latter, in the manner above described, is presented by the operator to the suction slits 11', 11'. The stem 18 at its other end is secured to the upper portion of a metal plate 20, slightly spaced from the wall 12 except along its lower edge portion, the latter being anchored to said wall 12 as by means of screws 21, 21, or the like. At an intermediate point, between its upper and lower portions, the plate 20 has a threaded hole receiving an adjusting screw 22 of very fine pitch, said screw 22 passing through the wall 12, with its head exposed on the surface 6' to permit it to be manipulated for slight flexures of the plate 20, thereby to vary or adjust very delicately the spacing of the chisel-point from the surface 6. By setting this device to the desired spacing, the operator can make sure that each splitting or filming operation will be started, due to a slight penetration or piercing of the book edge, in a plane of cleavage whose distance from the surface 6 is the approximate thickness 75 of the desired mica films or splits, whether the

latter be a single lamination or two or more laminations of the material.

I claim:

1. The herein described treatment of sheet mica in book or block form to facilitate its splitting or filming, which consists in immersing the mica in water containing an aliphatic ester of sulfodicarboxylic acid in sufficient amount to materially reduce the surface tension of the water and prolonging said immersion substantially in proportion to the strength of the natural bond or adhesion between the laminations of said material.

2. The herein described treatment of sheet mica in block or book form to facilitate its splitting or filming, which consists in plunging the same into water containing a small percentage of a diethyl ester of sulfosuccinate the effect of which is to materially reduce the surface tension of the water.

3. The herein described treatment of sheet mica in block or book form to facilitate its splitting or filming, which consists in immersing the books in water containing a small amount of "aerosol O. T. 10%" solution the effect of which is to materially reduce the surface tension of the water.

4. The herein described treatment of sheet mica in block or book form to facilitate its splitting or filming, which consists in immersing the books in water containing a small amount of "aerosol O. T. 10%" solution, namely, twenty-five drops of said solution to each quart of water the effect of which is to materially reduce the surface tension of the water.

5. The herein described treatment of sheet mica in block or book form to facilitate its splitting or filming, which consists in subjecting it to a water bath containing in solution a small amount of the wetting agent known as "aerosol" and a few drops of ammonia.

6. In the art of splitting or filming sheet mica, the improvement which consists in holding a mica book in fixed position, by suction applied to its face, against a surface which falls away from the plane of said book, and then deflecting the book toward said surface, whereby to peel or strip it bodily from the suctionally held outside lamination thereof.

7. In the art of splitting or filming sheet mica, the improvement which consists in supporting a mica book in fixed position by suction effective on a limited area of the book's face near one edge thereof, and then, by pressure against the free edge of the book, procuring a planar deflection thereof which strips it bodily from the suctionally-held lamination.

8. In the art of splitting or filming sheet mica, the improvement which consists in gripping and holding a mica book in fixed position near one edge of its face by suction exerted through a surface which extends in divergent relation to the remainder of said face, and then subjecting the so-supported book to planar deflection in the direction of said surface, to strip it bodily from the suctionally-held external lamination.

9. In the art of splitting or filming sheet mica, the improvement which consists in engaging a mica book in a limited area near one edge of its face with suction apertures, the latter being provided by a fixed surface which stands in divergent relation to the remaining face area of the so-supported book, and then, by pressure against the free edge of said book in the direction of said divergent surface, procuring a planar deflection to strip the same bodily from the suctionally-held external lamination thereof.

10. In the art of splitting or filming sheet mica, the improvement which consists in suctionally gripping and holding a mica book at a limited face area near one edge in fixed position, and then tilting the plane of said book about a fulcrum between its free edge and the suctionally gripped face zone, to strip said book bodily from its suctionally-held external lamination.

11. In the art of splitting or film sheet mica, the improvement which consists in suctionally gripping and holding stationary a mica book, in a limited face area near one edge, simultaneously engaging and piercing said edge in a plane of cleavage having a predetermined spacing from the suctionally-engaged outside lamination of said book, and then tilting the plane of said book about a fulcrum between the book's free edge and its suctionally-gripped face zone, to divide said book on said plane of cleavage.

12. A device for use in the splitting or filming of sheet mica, comprising a stationary body having suction apertures adapted to support and hold stationary a mica book by contact with a face thereof near one edge, said body providing a fulcrum for the planar tilting of said book, between the latter's free edge and said suction apertures, and means on the opposite side of said suction apertures from said fulcrum to pierce said book edge in a plane of cleavage at a predetermined spacing from the suctionally-held outer surface area.

13. In the art of splitting or filming sheet mica, the improvement which consists in soaking each mica book in water containing an ester of dicarboxylic or sulfodicarboxylic acid in sufficient amount to reduce materially the interfacial tension between water, mica and air, then supporting and holding the so-treated book in fixed position by suction effective on the face of an external lamination, near one edge thereof, and finally, by pressure applied near the free edge of said book, procuring its planar deflection to strip it bodily from said suctionally-held lamination.

14. In the art of splitting or filming sheet mica, the improvement which consists in immersing each mica book in water containing an organic water-soluble wetting agent or surface-active material in sufficient amount to materially reduce the water's surface tension, prolonging such immersion substantially in proportion to the strength of the natural bond or adhesion between the laminations of the book, procuring with each so-treated book successive contacts with suction apertures effective over a limited face area near one edge of said book, to stationarily support said book with its remaining face area in a plane divergent from the surface containing such suction apertures, and, during each period of such support, urging said book toward said surface by pressure applied near its free edge, thereby procuring its planar deflection to strip the same bodily from the suctionally-held external lamination thereof.

15. In the art of splitting or filming sheet mica, the improvement which consists in soaking each mica book in water containing a small amount of "aerosol O. T. 10%" solution, thereby through the materially lowered surface tension of said water to obtain the latter's penetration between the laminations of said book, presenting the so-treated book successively to suction apertures formed in a convex surface, to stationarily support said book, tangentially to said surface, by suction exerted on the face of an external lamination near one edge of the book and in the

period of each such support, producing the book's planar deflection toward said surface, whereby to peel or strip it bodily from its suctionally-held external lamination.

16. In the art of splitting or filming sheet mica, the improvement which consists in soaking each book in a moderately heated water bath containing the wetting agent "aerosol" and a few drops of ammonia in sufficient amount to materially reduce the water's surface tension, procuring successive supports of said book, by suction applied to its face, near one edge thereof, against a surface which falls away from the plane of the so-supported book, and in the instance of each such support, causing planar deflection of the book toward said surface, to peel or strip it bodily from its suctionally-held external lamination.

17. In the production of mica films and splittings from book mica, the improvement which consists in submerging the book material in water containing the wetting agent known as "aerosol" in sufficient amount to materially reduce the water's surface tension, thereby enabling it to penetrate any breaks or gaps in the bond between the material's layers, prolonging such submergence a sufficient time for the penetrant liquid to attack and weaken said bond, thereby to promote formation of cleavage planes between said layers, and then splitting said material in said planes.

18. In the production of mica films and splittings from book mica, the improvement which consists in submerging the book material in water containing the wetting agent "aerosol" in sufficient amount to materially reduce the water's surface tension, thereby enabling it to penetrate any breaks or gaps in the bond between the material's layers, prolonging such submergence a sufficient time for the penetrant liquid to attack and weaken said bond, thereby to establish planes of cleavage between said layers, and then splitting said material on the planes of cleavage so established.

19. In the splitting or filming of book mica which has been previously treated to reduce the strength of the bond or adhesion between its layers, the improvement which consists in repeatedly manipulating the book material, to establish cleavages between its residue and the successively-exposed external layers thereof, in the following sequence or order, viz., (1) supporting the material in fixed position by suction effective on its face near one edge thereof, against a surface which falls away from the plane of the so-supported material, and (2) procuring a planar deflection of said material toward said surface, to open up a cleavage plane between the suctionally held face lamination and the remainder of said material.

20. In the splitting or filming of book mica which has previously been treated to reduce the strength of the bond or adhesion between its layers, the improvement which consists in repeatedly manipulating the book material, to effect cleavages between itself and successively-exposed surface layers thereof, in the following order or sequence, viz., (1) presenting a face of the material near one edge to suction apertures provided by a fixed convex surface, thereby to support said material substantially in tangential relation to said surface, and (2) pressing the free edge of said material toward said surface, thereby to open up a plane of cleavage at the opposite edge be-

tween the suctionally-gripped layer and the remaining layers.

21. Mica splitting apparatus, including a device having a generally convex surface and an adjacent aperture, means for exerting suction through said aperture, and a projection adjacent said aperture and minutely offset from said surface in position to pierce the edge of a mica book presented facewise to said aperture and held by said suction in substantially tangential relation to said surface.

22. Mica splitting apparatus, including a device having a generally convex surface and an adjacent aperture, means for exerting suction through said aperture, a projection adjacent said aperture and minutely offset from said surface in position to pierce the edge of a mica book presented facewise to said aperture and held by said suction in substantially tangential relation to said surface, and means for adjusting the offset of said projection from said surface.

23. In the splitting or filming of book mica, the improvement which consists in first soaking the books in a water bath containing an organic water-soluble wetting agent whose effect is to materially reduce the interfacial tension between water, mica and air, then stationarily supporting each book so-treated repeatedly by successive presentations of its face, near one edge, to a suction aperture provided in a surface which falls away from the plane of the so-supported book, and after each such presentation procuring the planar deflection of the book toward said surface by finger pressure thereon at a point appreciably removed from said suctionally-engaged portion, whereby to strip the book-residue bodily from the successive suctionally-held external laminations thereof.

24. The herein-described method of splitting or filming book mica which consists in repeatedly presenting a book, for temporary stationary support by face engagement therewith, to suction means effective only on an edge portion of said face, and in each period of support, by finger pressure exerted on said book at a point remote from its support zone, procuring its planar deflection, to initiate stripping or cleavage of the residue of book material away from the suctionally-held face lamination thereof.
